UNITED STATES PATENT OFFICE.

WILLIAM J. KNOBLOCH, OF WASHINGTON, DISTRICT OF COLUMBIA.

ELECTRIC ALARM.

1,026,518.

Specification of Letters Patent.

Patented May 14, 1912.

Application filed December 4, 1911. Serial No. 663,768.

To all whom it may concern:

Be it known that I, WILLIAM J. KNOBLOCH, citizen of the United States, residing at Washington, in the District of Columbia, 5 have invented certain new and useful Improvements in Electric Alarms, of which the following is a specification.

This invention has relation to electric alarms especially adapted to be applied to 10 refrigerators and the like for the purpose of sounding a warning when the water in the drip pan in the refrigerator has attained a certain level.

With this object in view the invention 15 consists of a frame of peculiar configuration which is adapted to be applied to a fixed part of the refrigerator and from which hangs an arm which is hingedly connected with the frame. This arm is adapted to 20 sustain a float which is to be projected into the pan or removable vessel of the refrigerator. This arm is especially designed and is in the main insulated from the frame, but is provided with a finger which is adapted 25 to have contact with the frame, whereby an electric circuit is completed from a battery and buzzer mounted upon the frame.

For a full understanding of the invention reference is to be had to the following description and accompanying drawing, in 30 which:

Figure 1 is a side elevation of the alarm; Fig. 2 is an under view with part in section; Fig. 3 is a plan view of the plate 35 frame; Fig. 4 is a perspective view; and Fig. 5 is a sectional view of part of the device.

Corresponding and like parts are referred to in the following description and indicated in all the views of the accompanying drawing by the same reference characters.

The frame of the alarm consists of a plate 1 which is formed preferably from sheet metal and which is bounded about its 45 edge with a stiffening corrugation 2. The metal of which the said frame is composed is cut away forming downwardly disposed lugs 3 which are adapted to slidably receive a battery 4 and sustain the same. One pole of 50 the battery 4 is connected by means of a wire 5 with a binding post 6 mounted upon the frame. Another part of the frame is stamped up forming a lug 7 which is adapted to coöperate with a finger of a hinged

arm, to be explained hereinafter, for the 55 purpose of completing an electric circuit through the alarm. A buzzer 8 or equivalent alarm device is mounted upon the plate 1 and is connected with the other pole of the battery 4 by means of a strip 9.

Adjacent the buzzer 8 the metal of the plate 1 is cut out and curled up forming a sleeve 10. A hinge pin passes through the said sleeve and is insulated from the same by insulating material 12. An arm 13 is 65 provided at its upper end with curls 14 which receive the end portions of the hinge pin 11. The said arm is provided at one side with a finger 15 formed from the metal of which the said arm is composed and 70 which is adapted at times to encounter the lug 7. The said arm 13 is also provided with a finger 16 which is formed up of the metal of which the frame is composed, and a binding post 17 is mounted upon the finger 75 16. A wire 18 connects the binding post 17 with the buzzer 8. The lower portion of the arm 13 is slotted longitudinally forming three fingers 19 which are bowed outwardly 80 at their intermediate portions and which are disposed from each other at their lower ends. A ball float 20 is sustained between the fingers 19.

The device as above described is applied to a fixed part of a refrigerator and the ball 85 20 is permitted to hang in the upper portion of the pan thereof. When the water in the pan attains a certain level and comes in contact with the ball 20 the said ball is elevated, whereby the arm 13 is swung and the finger 90 15 thereof is brought in contact with the lug 7. Thus an electric circuit is completed through the buzzer and battery and frame and their connecting parts, and the wire 18 and the arm 13 and the buzzer is excited and 95 gives out an alarm. As soon as the pan is removed from under the ball 20 the said ball falls by gravity and the arm 13 is swung so that its finger 15 is carried away from the lug 7 and the circuit is broken and the buzzer ceases to sound. The arm 13 possesses 100 sufficient resiliency to permit the ball 20 to slide freely over the edge of the pan as the pan is inserted under the alarm or withdrawn from under the same.

The parts are compactly assembled and may be readily applied to any known form of refrigerator or similar apparatus, and

when the battery becomes exhausted it may be readily slipped from between the lugs 3 and a new one substituted in its stead.

Having thus described the invention, what is claimed as new is:

1. An electric alarm comprising a frame having a battery and a buzzer located thereon, an electric connection between the battery and buzzer, an electric connection between the battery and frame, an arm hingedly mounted upon the frame and insulated therefrom, said arm being formed from a strip of sheet material, a portion of the material of which the arm is formed being struck up into a finger adapted to encounter the frame at times, a second finger formed up from the arm and a wire connecting the last mentioned finger with the buzzer, the strip of which the arm is formed having at its lower end longitudinally disposed slits forming fingers which are bowed from each other at their intermediate portions and which are disposed toward each other at their lower ends, a ball inserted between the last mentioned fingers.
2. An electric alarm comprising a frame having a battery and buzzer mounted thereon, an electric connection between the bat-

tery and buzzer, an electric connection between the battery and the frame, an arm hingedly mounted upon the frame and insulated therefrom, said arm being formed from a strip of sheet material, a portion of the material of which the arm is formed being struck up into a finger adapted to encounter the frame at times, a second finger formed up from the arm and a wire connecting the last mentioned finger with the buzzer, the strip of which the arm is formed having at its lower end longitudinally disposed slits forming three fingers which are bowed from each other at their intermediate portions and which are disposed toward each other at their lower ends, a ball inserted between the last mentioned fingers, the said arm having sufficient resiliency to permit the said ball to be brushed to one side or the other as a pan is inserted under the same or removed from under the same.

In testimony whereof I affix my signature in presence of two witnesses.

WILLIAM J. KNOBLOCH.
